OVEN CLOTHES-DRYER

Aaron J. Weiss, Los Angeles, Calif.

Application June 22, 1955, Serial No. 517,349

10 Claims. (Cl. 34—90)

Generally speaking, the present invention relates to the clothes-dryer art and, more particularly, pertains to a clothes-dryer adapted to be inserted into a home oven, and energized by an electric source, to allow the effective heating, tumbling and ventilation of fabrics placed therein to remove moisture therefrom.

I am aware that many home clothes-dryers have been invented and developed heretofore; but all such prior devices, known to me, have suffered from numerous disadvantages. They are provided with their own cabinets, heat sources, electric and often gas connections, and in their mechanical workings are quite complex; thus they are exceedingly expensive, and are not economic for most homes. Further, their cabinets occupy a great deal of space, much of which is waste space—and space is of value in a small house or apartment. However, a compact, inexpensive clothes dryer would be of great value in most homes; it is to answer this need that the present invention has been developed.

Generically speaking, the present invention comprises support-case means slidably insertible into the oven of a household range or the like, having front wall means by which the entrance-aperture at the front of the oven can be effectively closed against the uncontrolled flow of air therethrough (i. e., the flow of air around said wall means is blocked); tumbler-drum means consisting of multiple apertured cylindrical shell means having rear fully closed end means and having front partially closed end means (spaced from said rear end means) with fabric-inlet aperture therein, said tumbler-drum means being rotatably held by said support-case means to have said fabric-inlet aperture adjacent said front wall means and to be rotatable about a longitudinal axis of said shell means, usually virtually perpendicular to said front wall means; said front wall means being provided with selectively closable door means cooperable, when open, with said fabric-inlet aperture to allow fabrics to be placed within said tumbler-drum means; rotary fan means, cooperable with said tumbler-drum means to be in rotatably driven relationship thereto, and a fan-aperture defined by said front wall means, said fan being mounted in said fan-aperture to selectively force air into said oven (when in use); an air-exit aperture defined by said front wall means; and motor means, energizably connectible to an electric source, in rotatably driving relationship to said tumbler-drum means.

In one generic form of the present invention, at said fully closed end means the tumbler-drum means is connected by a (co-axial thereto) shaft and bearing to rear wall means of said support-case means, which also has side wall means and apertured bottom means (said bottom means, which is supportedly cooperable with the bottom of the oven, may carry insulation on its lower side) which are joined to said front wall means. Said tumbler-drum means is provided with annular track means adjacent its partially closed end (co-axial with the cylindrical shell) and said front wall means is provided with a plurality of roller means cooperable to rollably support said track

2

means and thus support and stabilize the tumbler-drum means.

In one preferred form of the present invention, the tumbler-drum means, rotary fan means, and motor means (usually supported by said front wall means) are in pulley-relationship to a single drive belt. In a second preferred form, the tumbler-drum means and fan means are in pulley-relationship to a single drive belt, with said axial shaft in removably engageable relation to a rotational coupling (to be rotationally driven thereby) which, with said motor means (which is in driving relationship thereto) may be mounted at the back of the oven itself in a (more or less) permanent fashion.

In some forms of the present invention, the tumbler-drum means may be provided with a plurality of longitudinal fins, mounted within (on the inner surface of) said cylindrical shell angularly spaced from each other, to increase the fabric-tumbling action of the tumbler-drum means.

20 To use the clothes-dryer of the present invention, one first places it in an oven; opens said door means and places fabric materials (damp clothes, e. g., previously "damp-dried" by a wringer or centrifuge) within the tumbler-drum means; closes said door means, turns on the oven heat, and energizes said motor means to actuate the tumbler-drum and fan means. The fabric materials are then tumbled, heated by air passing through the tumbler-drum apertures, and ventilated until dry (the oven temperature soon stabilizes at a "warm" level).

25 From the above description of the basic form and various preferred forms of the present invention, it will be apparent to those skilled in the art that the hereinabove-mentioned disadvantages of prior clothes dryers are virtually entirely eliminated and overcome in and through 30 the use of the present invention.

For example, the present invention makes use of a cabinet and heat source—namely a range oven—which are ordinarily found in a home, and is of mechanically simple but effective construction; thus the present invention can be manufactured at low cost. Further, it is extremely compact; it can ordinarily be stored, in place, in the oven, but will occupy little space when removed from the oven to permit the oven's use in cooking.

35 With the above points in mind, it is an object of the present invention to provide an electrically operated clothes-dryer adapted to be inserted into an oven and cooperable with said oven to heat, tumble, and ventilate fabric materials placed therein to remove moisture therefrom.

40 It is also an object of the present invention to provide inexpensive and compact apparatus cooperable with the oven of a home range to form an effective clothes-dryer and readily removable from said oven.

45 Other and allied objects of the present invention will occur to those skilled in the art after a careful study of the present specification, the accompanying illustrations, and the appended claims.

To facilitate understanding, reference will be made to the hereinbelow-described drawings, in which:

50 Fig. 1 is a perspective view of a preferred embodiment of the present invention as it appears (from the front) when placed in an oven ready for use;

55 Fig. 2 is a perspective view of the device of Fig. 1 as it appears (from a rear vantage point) when removed from the oven (a portion of said side wall means being broken away for clarity);

60 Fig. 3 is a sectional view of the device of Fig. 1, the plane and direction of the section being indicated by the line and arrows III—III of Fig. 2;

65 Fig. 4 is a sectional view of the device of Fig. 1, the plane and direction of the section being indicated by the line and arrows IV—IV of Fig. 2;

Fig. 5 is an enlarged detail of the sectional view of Fig. 3;

Fig. 6 is a view, similar to Fig. 5 in location, of a portion of a modified form of the device of Fig. 1;

Fig. 7 is a perspective view of a second preferred embodiment of the present invention, installed in an oven, various parts invisible from this vantage being indicated by dashed lines; and

Fig. 8 is a sectional view of a portion of the device of Fig. 7, the position and direction of the section being indicated by the line and arrows VIII—VIII of Fig. 7.

The parts of the modified form of Fig. 6 similar to those of the device of Fig. 1 will be numbered similarly, but with primed reference numerals; the parts of the embodiment illustrated in Figs. 7 and 8 similar to the parts of the device of Fig. 1 will be numbered similarly, but with doubly primed numerals.

Generally speaking, the present invention includes support-case means made up of front end-wall means, side wall means, rear wall means, and apertured bottom means; in the specific form illustrated in Figs. 1-5, the support-case is formed by front end-wall 1, sidewalls 2a and 2b, rear wall 3, and bottom 4 carrying insulation (e. g., asbestos) at 5 and defining apertures 6 to permit heat from the oven-bottom to pass therethrough. Also, generally speaking, the present invention includes multiply apertured tumbler-drum means rotatably mounted on said support-case means; in the illustrated form, the tumbler-drum consists of metal cylindrical shell 7, having a plurality of apertures 8 therein, having a closed end—closed by metal disc 9, and having a front end partially closed by the generally annular member 10, which defines a central aperture A. Attached to disc 9 is shaft 11, supported by the thrust-type ball-bearing 12 held by rear wall 3. Within the shell 7, four longitudinal fins 13 are attached to the shell, angularly spaced from each other, to aid in tumbling fabrics placed in the shell when it is rotated in use.

Generally speaking, the front end-wall means is provided with door means; in the illustrated form, opposite tumbler-drum aperture A is an aperture, in front end-wall 1, which is shown closed by a door 14 hinged by pin 15 to a projection 16 of the front end-wall 1 and having a handle 17 by which it may be pulled open to permit fabrics to be introduced or removed through aperture A. Said front end-wall means, generally speaking, defines a fan-aperture, in which rotary fan means is mounted to be in rotatably driven relationship to the tumbler-drum means; in the illustrated form, aperture B in end-wall 1 holds rotary fan 18, which has a fan pulley 19 driven by a belt 20 which passes around the track 21, mounted circumferentially on cylindrical shell 7 at the front end.

Also, generally speaking, the tumbler-drum means is rotatably mounted at its front end, having track means supported by roller means rotatably mounted on end-wall 1. In the form of the track and roller means explicitly shown in Figs. 3, 4, and 5, the track means is constituted by the portion 7a of shell 7 between its front edge and a lip 10a of annular member 10. The four shafts 22 rotatably support rollers 23, which ride in track 7a, rotatably supporting the tumbler-drum. In the modified form explicitly shown in Fig. 6, a circumferential ring 24 is attached, e. g. by bolts as shown at 25, to annular member 10' and shell 7'; belt 20' rides in a track-portion 24a of the ring; shafts 22' hold grooved rollers 26, which ride on the track formed by inner rim 24b of ring 24. The rollers shown in the two forms of Figs. 5 and 6 ride "hypocyclicly" with respect to the shell; it would also be possible to use "epicyclic" rollers (riding on the outside of the shell) at some sacrifice of compactness.

Further, generally speaking, the present invention includes motor means in rotatable driving relationship to the tumbler-drum means. In the first embodiment illustrated, as seen explicitly in Figs. 1-4, a motor 27 is

mounted on end-wall 1, and has a drive pulley 28 in driving relationship to belt 20, thus driving the tumbler-drum (and fan). To energize the motor, it may be connected to an electric source (not shown). In the embodiment of Figs. 7 and 8, motor 27" has a worm-shaft 29 which with gear 30 forms a reduction-drive for (square-cross-sectioned) male shaft 31, held in roller-bearing 12"; onto shaft 31, female shaft 11" from the tumbler-drum (which rests on saddle bearing 32) may be removably rotatably-drivably engaged. The motor 27" and bearing 12" are fixedly mounted on the back wall of an oven D', into which the remainder of the clothes-dryer apparatus may be inserted, shaft 11" being thus engaged with shaft 31 (which passes into the oven at aperture 35), when the device is to be used or stored between other uses of the oven; that is, the motor assembly is more or less built into the range, to give the advantages of a fixed motor installation—proper heat, sound, and electric insulation are more easily used, and the electrical connections (not shown) may be made simple and convenient. With the single exception of the motor assembly, the form of Figs. 7 and 8 is similar to that of Figs. 1-5.

Also, generally speaking, the front end-wall means of the present invention defines an air-exit aperture; in the form illustrated (but explicitly only in Figs. 1, 2 and 4) the aperture C in end-wall 1 is provided with a lint-filter screen 33. In Fig. 1, the clothes-dryer is shown ready for use in an oven D, having a heat-control 34 (which may be set, if thermostatic, at a temperature-reading at or somewhat above the operating-temperature chosen for the clothes-dryer—this operating-temperature is determined by the air-flow from the fan, which removes heat from the oven). The end-wall 1 blocks the entrance to the oven; when the clothes-dryer is in use, air is forced into the oven through aperture B by fan 18, exiting through aperture C, whose lint-filter screen 33 prevents lint and fuzz from fabrics in the tumbler-drum from escaping. The motor, in any of the forms of the clothes-dryer, should (through its speed-reduction by belt or worm-gear) drive the tumbler-drum at an angular speed which will (with the aid of fins 13) give a tumbling action to fabrics held within—that is, the centrifugal acceleration on the fabrics should be in the neighborhood of one "g" or gravity.

Numerous modifications and variations of the present invention will occur to those skilled in the art after a careful study hereof. All such, properly within the basic spirit and scope of the present invention are intended to be included and comprehended herein as fully as if specifically described, illustrated and claimed herein.

For example, the number and location of the fins inside the tumbler-drum may be varied, or the fins may be eliminated. The rotary fan could be used in the air-exit aperture (C) as an exhaust fan, instead of as an intake fan in the inlet aperture (B). Although the clothes-dryer has been described as usable with the oven of a home range, it may, of course, be used in any similar heatable compartment.

The exact compositions, configurations, constructions, relative positionings, and cooperative relationships of the various component parts of the present invention are not critical, and can be modified substantially within the spirit of the present invention.

The embodiments of the present invention specifically described and illustrated herein are exemplary only, and are not intended to limit the scope of the present invention, which is to be interpreted in the light of the prior art and the appended claims only, with due consideration for the doctrine of equivalents.

I claim:

1. A clothes-dryer adapted to be inserted into an oven and energized by an electric source to tumble, ventilate, and allow the effective heating of fabrics placed therein to remove moisture therefrom, comprising: support-case means slidably insertible into an oven, including front

wall means effectively closingly cooperable, to virtually prevent the flow of air therearound, with a front entrance-aperture of said oven; tumbler-drum means including cylindrical shell means having a longitudinal axis, having a plurality of apertures therethrough, having rear closed end means, and having front end means defining a fabric-inlet aperture and being spaced from said rear end means; said tumbler-drum means being supportedly connected to said support-case means, with said front end means adjacent said front wall means, to be rotatable about said longitudinal axis; said front wall means being provided with selectively closable door means cooperable, when open, with said fabric-inlet aperture to allow fabrics to be placed within said cylindrical shell means; said front wall means defining a fan-aperture and an air-exit aperture; rotary fan means cooperable in rotatably driven relationship with said tumbler-drum means and mounted in said fan-aperture to selectively force air into said oven; and motor means, energizably connectible to an electric source, in rotatably driving relationship to said tumbler-drum means; whereby, when said oven is supplied with heat, the clothes-dryer placed therein, and said motor energized, fabrics placed within said cylindrical shell means may be tumbled, heated, ventilated by air passing through the apertures in said shell means, and thus dried, the resulting moist air being removed from the oven by the cooperation of said fan means with said fan aperture and air-exit aperture to force air therethrough.

2. A clothes-dryer adapted to be inserted into an oven and energized by an electric source to tumble, ventilate, and allow the effective heating of fabrics placed therein to remove moisture therefrom, comprising: support-case means slidably insertible into an oven, including front wall means effectively closingly cooperable, to virtually prevent the flow of air therearound, with a front entrance-aperture of said oven; tumbler-drum means including cylindrical shell means having a longitudinal axis, having a plurality of apertures therethrough, having rear closed end means, and having front end means defining a fabric-inlet aperture and being spaced from said rear end means; rotational connection means rotatably and supportingly connecting said tumbler-drum means to said support-case means, with said front end means lying adjacent said front wall means, allowing said tumbler-drum means to be rotatable about said longitudinal axis; said front wall means being provided with selectively closable door means cooperable, when open, with said fabric-inlet aperture to allow fabrics to be placed within said cylindrical shell means; said front wall means defining a fan-aperture and an air-exit aperture; rotary fan means cooperable in rotatably driven relationship with said tumbler-drum means and mounted in said fan-aperture to selectively force air into said oven; and motor means, energizably connectible to an electric source, in rotatably driving relationship to said tumbler-drum means; said support-case means including apertured bottom means, supportedly cooperable with the bottom of said oven and connected to said front wall means, and rear wall means connected to said bottom means spaced from said front wall means; said rotational connection means including shaft and bearing means coaxial with said shell means and supportedly connecting said rear closed end means to said rear wall means, and including annular track means held, coaxial with said shell means, by said tumbler-drum means adjacent said front end and a plurality of roller means rotatably held by said front wall means in rollable supporting and stabilizing relationship to said track means; whereby, when said oven is supplied with heat, the clothes-dryer placed therein, and said motor energized, fabrics placed within said cylindrical shell means may be tumbled, heated, ventilated by air passing through the apertures in said shell means, and thus dried, the resulting moist air being removed from the oven by the cooperation of said fan means with said fan aperture and air-exit aperture to force air therethrough.

3. A clothes-dryer adapted to be inserted into an oven and energized by an electric source to tumble, ventilate, and allow the effective heating of fabrics placed therein to remove moisture therefrom, comprising: support-case

means slidably insertible into an oven, including front wall means effectively closingly cooperable, to virtually prevent the flow of air therearound, with a front entrance-aperture of said oven; tumbler-drum means including cylindrical shell means having a longitudinal axis, having a plurality of apertures therethrough, having rear closed end means, and having front end means defining a fabric-inlet aperture and being spaced from said rear end means; rotational connection means rotatably and supportingly connecting said tumbler-drum means to said support-case means, with said front end means lying adjacent said front wall means, allowing said tumbler-drum means to be rotatable about said longitudinal axis; said front wall means being provided with selectively closable door means cooperable, when open, with said fabric-inlet aperture to allow fabrics to be placed within said cylindrical shell means; said front wall means defining a fan-aperture and an air-exit aperture; rotary fan means cooperable in rotatably driven relationship with said tumbler-drum means and mounted in said fan-aperture to selectively force air into said oven; and motor means, energizably connectible to an electric source, in rotatably driving relationship to said tumbler-drum means; said support-case means including apertured bottom means, supportedly cooperable with the bottom of said oven and connected to said front wall means, and rear wall means connected to said bottom means spaced from said front wall means; said rotational connection means including shaft and bearing means coaxial with said shell means and supportedly connecting said rear closed end means to said rear wall means, and including annular track means held, coaxial with said shell means, by said tumbler-drum means adjacent said front end and a plurality of roller means rotatably held by said front wall means in rollable supporting and stabilizing relationship to said track means; whereby, when said oven is supplied with heat, the clothes-dryer placed therein, and said motor energized, fabrics placed within said cylindrical shell means may be tumbled, heated, ventilated by air passing through the apertures in said shell means, and thus dried, the resulting moist air being removed from the oven by the cooperation of said fan means with said fan aperture and air-exit aperture to force air therethrough.

4. A clothes-dryer adapted to be inserted into an oven and energized by an electric source to tumble, ventilate, and allow the effective heating of fabrics placed therein to remove moisture therefrom, comprising: support-case means slidably insertible into an oven, including front wall means effectively closingly cooperable, to virtually prevent the flow of air therearound, with a front entrance-aperture of said oven; tumbler-drum means including cylindrical shell means having a longitudinal axis, having a plurality of apertures therethrough, having rear closed end means, and having front end means defining a fabric-inlet aperture and being spaced from said rear end means; longitudinal fin means mounted within said cylindrical shell means to increase the fabric-tumbling action thereof; rotational connection means rotatably and supportingly connecting said tumbler-drum means to said support-case means, with said front end means lying adjacent said front wall means, allowing said tumbler-drum means to be rotatable about said longitudinal axis; said front wall means being provided with selectively closable door means cooperable, when open, with said fabric-inlet aperture to allow fabrics to be placed within said cylindrical shell means; said front wall means defining a fan-aperture and an air-exit aperture; rotary fan means cooperable in rotatably driven relationship with said tumbler-drum means and mounted in said fan-aperture to selectively force air into said oven; and motor means, energizably connectible to an electric source, in rotatably driving relationship to said tumbler-drum means; whereby, when said oven is supplied with heat, the clothes-dryer placed therein, and said motor energized,

fabrics placed within said cylindrical shell means may be tumbled, heated, ventilated by air passing through the apertures in said shell means, and thus dried, the resulting moist air being removed from the oven by the co-operation of said fans means with said fan aperture and air-exit aperture to force air therethrough.

5. A clothes-dryer adapted to be inserted into an oven and energized by an electric source to tumble, ventilate, and allow the effective heating of fabrics placed therein to remove moisture therefrom, comprising: support-case means slidably insertible into an oven, including front wall means effectively closingly cooperable, to virtually prevent the flow of air therearound, with a front entrance-aperture of said oven; tumbler-drum means including cylindrical shell means having a longitudinal axis, having a plurality of apertures therethrough, having rear closed end means, and having front end means defining a fabric-inlet aperture and being spaced from said rear end means; rotational connection means rotatably and supportingly connecting said tumbler-drum means to said support-case means, with said front end means lying adjacent said front wall means, allowing said tumbler-drum means to be rotatable about said longitudinal axis; said front wall means being provided with selectively closable door means cooperable, when open, with said fabric-inlet aperture to allow fabrics to be placed within said cylindrical shell means; said front wall means defining a fan-aperture and an air-exit aperture; rotary fan means cooperable in rotatably driven relationship with said tumbler-drum means and mounted in said fan-aperture to selectively force air into said oven; motor means, energizably connectible to an electric source and held by said front wall means; and belt means connecting said motor in rotating driving relationship with said tumbler-drum means and said rotary fan means; whereby, when said oven is supplied with heat, the clothes-dryer placed therein, and said motor energized, fabrics placed within said cylindrical shell means may be tumbled, heated, ventilated by air passing through the apertures in said shell means, and thus dried, the resulting moist air being removed from the oven by the cooperation of said fan means with said fan aperture and air-exit aperture to force air therethrough.

6. A clothes-dryer adapted to be inserted into an oven and energized by an electric source to tumble, ventilate, and allow the effective heating of fabrics placed therein to remove moisture therefrom, comprising: support-case means slidably insertible into an oven, including front wall means effectively closingly cooperable, to virtually prevent the flow of air therearound, with a front entrance-aperture of said oven; tumbler-drum means including cylindrical shell means having a longitudinal axis, having a plurality of apertures therethrough, having rear closed end means, and having front end means defining a fabric-inlet aperture and being spaced from said rear end means; rotational connection means rotatably and supportingly connecting said tumbler-drum means to said support-case means, with said front end means lying adjacent said front wall means, allowing said tumbler-drum means to be rotatable about said longitudinal axis; said front wall means being provided with selectively closable door means cooperable, when open, with said fabric-inlet aperture to allow fabrics to be placed within said cylindrical shell means; said front wall means defining a fan-aperture and an air-exit aperture; rotary fan means cooperable in rotatably driven relationship with said tumbler-drum means and mounted in said fan-aperture to selectively force air into said oven; motor means, energizably connectible to an electric source and held by said front wall means; and belt means connecting said motor in rotating driving relationship with said tumbler-drum means and said rotary fan means; said support-case means including apertured bottom means, supportedly cooperable with the bottom of said oven and connected to said front wall means, and rear wall means connected to said bottom means held, co-axial with said shell means, by said tumbler-drum means adjacent said front end and a plurality of roller means rotatably held by said front wall means in rollable supporting and stabilizing relationship to said track means; whereby, when said oven is supplied with heat, the clothes-dryer placed therein, and said motor energized, fabrics placed within said cylindrical shell means may be tumbled, heated, ventilated by air passing through the apertures in said shell means, and thus dried, the resulting moist air being removed from the oven by the cooperation of said fan means with said fan aperture and air-exit aperture to force air therethrough.

7. A clothes-dryer adapted to be inserted into an oven and energized by an electric source to tumble, ventilate, and allow the effective heating of fabrics placed therein to remove moisture therefrom, comprising: support-case means slidably insertible into an oven, including front wall means effectively closingly cooperable, to virtually prevent the flow of air therearound, with a front entrance-aperture of said oven; tumbler-drum means including cylindrical shell means having a longitudinal axis, having a plurality of apertures therethrough, having rear closed end means, and having front end means defining a fabric-inlet aperture and being spaced from said rear end means; longitudinal fin means mounted within said cylindrical shell means to increase the fabric-tumbling

means spaced from said front wall means; said rotational connection means including shaft and bearing means co-axial with said shell means and supportedly connecting said rear closed end means to said rear wall means; whereby, when said oven is supplied with heat, the clothes-dryer placed therein, and said motor energized, fabrics placed within said cylindrical shell means may be tumbled, heated, ventilated by air passing through the apertures in said shell means, and thus dried, the resulting moist air being removed from the oven by the co-operation of said fan means with said fan aperture and air-exit aperture to force air therethrough.

10. A clothes-dryer adapted to be inserted into an oven and energized by an electric source to tumble, ventilate, and allow the effective heating of fabrics placed therein to remove moisture therefrom, comprising: support-case means slidably insertible into an oven, including front wall means effectively closingly cooperable, to virtually prevent the flow of air therearound, with a front entrance-aperture of said oven; tumbler-drum means including cylindrical shell means having a longitudinal axis, having a plurality of apertures therethrough, having rear closed end means, and having front end means defining a fabric-inlet aperture and being spaced from said rear end means; rotational connection means rotatably and supportingly connecting said tumbler-drum means to said support-case means, with said front end means lying adjacent said front wall means, allowing said tumbler-drum means to be rotatable about said longitudinal axis; said front wall means being provided with selectively closable door means cooperable, when open, with said fabric-inlet aperture to allow fabrics to be placed within said cylindrical shell means; said front wall means defining a fan-aperture and an air-exit aperture; rotary fan means cooperable in rotatably driven relationship with said tumbler-drum means and mounted in said fan-aperture to selectively force air into said oven; motor means, energizably connectible to an electric source and held by said front wall means; and belt means connecting said motor in rotating driving relationship with said tumbler-drum means and said rotary fan means; said support-case means including apertured bottom means, supportedly cooperable with the bottom of said oven and connected to said front wall means, and rear wall means connected to said bottom means spaced from said front wall means; said rotational connection means including shaft and bearing means co-axial with said shell means and supportedly connecting said rear closed end means to said rear wall means, and including annular track means held, co-axial with said shell means, by said tumbler-drum means adjacent said front end and a plurality of roller means rotatably held by said front wall means in rollable supporting and stabilizing relationship to said track means; whereby, when said oven is supplied with heat, the clothes-dryer placed therein, and said motor energized, fabrics placed within said cylindrical shell means may be tumbled, heated, ventilated by air passing through the apertures in said shell means, and thus dried, the resulting moist air being removed from the oven by the cooperation of said fan means with said fan aperture and air-exit aperture to force air therethrough.

8. A clothes-dryer adapted to be inserted into an oven and energized by an electric source to tumble, ventilate, and allow the effective heating of fabrics placed therein to remove moisture therefrom, comprising: support-case means slidably insertible into an oven, including front wall means effectively closingly cooperable, to virtually prevent the flow of air therearound, with a front entrance-aperture of said oven; tumbler-drum means including cylindrical shell means having a longitudinal axis, having a plurality of apertures therethrough, having rear closed end means, and having front end means defining a fabric-inlet aperture and being spaced from said rear end means; longitudinal fin means mounted within said cylindrical shell means to increase the fabric-tumbling

action thereof; rotational connection means rotatably and supportingly connecting said tumbler-drum means to said support-case means, with said front end means lying adjacent said front wall means, allowing said tumbler-drum means to be rotatable about said longitudinal axis; said front wall means being provided with selectively closable door means cooperable, when open, with said fabric-inlet aperture to allow fabrics to be placed within said cylindrical shell means; said front wall means defining a fan-aperture and an air-exit aperture; rotary fan means cooperable in rotatably driven relationship with said tumbler-drum means and mounted in said fan-aperture to selectively force air into said oven; motor means, energizably connectible to an electric source and held by said front wall means; and belt means connecting said motor in rotating driving relationship with said tumbler-drum means and said rotary fan means; said support-case means including apertured bottom means, supportedly cooperable with the bottom of said oven and connected to said front wall means, and rear wall means connected to said bottom means spaced from said front wall means; said rotational connection means including shaft and bearing means co-axial with said shell means and supportedly connecting said rear closed end means to said rear wall means, and including annular track means held, co-axial with said shell means, by said tumbler-drum means adjacent said front end and a plurality of roller means rotatably held by said front wall means in rollable supporting and stabilizing relationship to said track means; whereby, when said oven is supplied with heat, the clothes-dryer placed therein, and said motor energized, fabrics placed within said cylindrical shell means may be tumbled, heated, ventilated by air passing through the apertures in said shell means, and thus dried, the resulting moist air being removed from the oven by the cooperation of said fan means with said fan aperture and air-exit aperture to force air therethrough.

9. A clothes-dryer adapted to be inserted into an oven and energized by an electric source to tumble, ventilate, and allow the effective heating of fabrics placed therein to remove moisture therefrom, comprising: support-case means slidably insertable into an oven, including front wall means effectively closingly cooperable, to virtually prevent the flow of air therearound, with a front entrance-aperture of said oven; tumbler-drum means including cylindrical shell means having a longitudinal axis, having a plurality of apertures therethrough, having rear closed end means, and having front end means defining a fabric-inlet aperture and being spaced from said rear end means; rotational connection means rotatably and supportingly connecting said tumbler-drum means to said support-case means, with said front end means lying adjacent said front wall means, allowing said tumbler-drum means to be rotatable about said longitudinal axis; said front wall means being provided with selectively closable door means cooperable, when open, with said fabric-inlet aperture to allow fabrics to be placed within said cylindrical shell means; said front wall means defining a fan-aperture and an air-exit aperture; rotary fan means cooperable in rotatably driven relationship with said tumbler-drum means and mounted in said fan-aperture to selectively force air into said oven; motor means, energizably connectible to an electric source and mountable on said oven means; and rotational coupling means rotatably drivable by said motor means; said support-case means including apertured bottom means, supportedly cooperable with the bottom of said oven and connected to said front wall means, and rear wall means connected to said bottom means spaced from said front wall means; said rotational connection means including shaft and bearing means co-axial with said shell means and

shell means and supportedly connecting said rear closed end means to said rear wall means; said shaft means being fixedly attached to said rear closed end means and being removably engageable with said rotational coupling means to be rotationally driven thereby; whereby, when said oven is supplied with heat, the clothes-dryer placed therein, and said motor energized, fabrics placed within said cylindrical shell means may be tumbled, heated, ventilated by air passing through the apertures in said shell means, and thus dried, the resulting moist air being removed from the oven by the cooperation of said fan means with said fan aperture and air-exit aperture to force air therethrough.

10. A clothes-dryer adapted to be inserted into an oven and energized by an electric source to tumble ventilate, and allow the effective heating of fabrics placed therein to remove moisture therefrom, comprising: support-case means slidably insertable into an oven, including front wall means effectively closingly cooperable, to virtually prevent the flow of air therearound, with a front entrance-aperture of said oven; tumbler-drum means including cylindrical shell means having a longitudinal axis, having a plurality of apertures therethrough, having rear closed end means, and having front end means defining a fabric-inlet aperture and being spaced from said rear end means; rotational connection means rotatably and supportingly connecting said tumbler-drum means to said support-case means, with said front end means lying adjacent said front wall means, allowing said tumbler-drum means to be rotatable about said longitudinal axis; said front wall means being provided with selectively closable door means cooperable, when open, with said fabric-inlet aperture to allow fabrics to be placed within said cylindrical shell means; said front wall means defining a fan-aperture and an air-exit aperture; rotary fan means cooperable in rotatably driven relationship with said tumbler-drum means and mounted in said fan-aperture to selectively force air into said oven; motor means, energizably connectible to an electric source and mountable on said oven means; and rotational coupling means rotatably drivable by said motor means; said support-case means including apertured bottom means, supportedly cooperable with the bottom of said oven and connected to said front wall means, and rear wall means connected to said bottom means spaced from said front wall means; said rotational connection means including shaft and bearing means co-axial with said shell means and supportedly connecting said rear closed end means to said rear wall means, and including annular track means held, co-axial with said shell means, by said tumbler-drum means adjacent said front end and a plurality of roller means rotatably held by said front wall means in rollable supporting and stabilizing relationship to said track means; said shaft means being fixedly attached to said rear closed end means and being removably engageable with said rotational coupling means to be rotationally driven thereby; whereby, when said oven is supplied with heat, the clothes-dryer placed therein, and said motor energized, fabrics placed within said cylindrical shell means may be tumbled, heated, ventilated by air passing through the apertures in said shell means, and thus dried, the resulting moist air being removed from the oven by the cooperation of said fan means with said fan aperture and air-exit aperture to force air therethrough.
